GARMENT HANGER

Reynolds Guyer, St. Paul, Minn., assignor to
 Waldorf Paper Products Company, St. Paul,
 Minn., a corporation of Minnesota

Application January 15, 1937, Serial No. 120,750

5 Claims. (Cl. 223—89)

My invention relates to garment hangers and has for an object to provide a hanger which may be easily and quickly collapsed or extended.

Another object of the invention resides in providing a hanger having a cross bar and converging supporting members hingedly connected together at their ends and in further providing means for connecting the other ends of the supporting member to the cross bar so that the supporting members may be folded into juxtaposed position with reference to the cross bar.

An object of the invention resides in utilizing links for connecting the cross bar to the supporting members whereby the supporting members may be swung into juxtaposition with respect to the cross bar.

A still further object of the invention resides in constructing the hanger from a strip of paper scored transversely at suitable intervals to form the supporting members, links and cross bar.

A feature of the invention resides in constructing the garment hanger from a tubular member bent at the required localities to form the various parts of the invention.

25 An object of the invention resides in providing reinforcing members disposed within the portion of the tube forming the cross bar.

30 A feature of the invention resides in constructing the garment hanger from a strip of paper bent in the form of a channel to reinforce and stiffen the same.

Other objects of the invention reside in the novel combination and arrangement of parts and in the details of construction hereinafter illustrated and/or described.

35 In the drawings:

Fig. 1 is a perspective view of a garment hanger illustrating an embodiment of my invention.

Fig. 2 is an elevational view of a coat supported 40 on a hanger such as shown in Fig. 1.

Fig. 3 is a developed view of the blank from which the hanger shown in Fig. 1 is constructed.

Fig. 4 is a perspective view of the reinforcing member used with the invention.

45 Fig. 5 is a cross sectional detail view taken on line 5—5 of Fig. 1.

Fig. 6 is a cross sectional detail view taken on line 6—6 of Fig. 1.

Fig. 7 is a longitudinal sectional detail view 50 taken on line 7—7 of Fig. 1.

Fig. 8 is a perspective view of the garment hanger shown in Fig. 1 collapsed.

Fig. 9 is a perspective view of a modified form 55 of the garment hanger.

Figs. 10 and 11 are developed views of the

blanks from which the garment hanger shown in Fig. 9 is constructed.

Fig. 12 is a perspective view of the reinforcing member used with the garment hanger shown in Fig. 9.

Fig. 13 is a cross sectional detail view taken on line 13—13 of Fig. 9.

Fig. 14 is a cross sectional detail view taken on line 14—14 of Fig. 9.

Fig. 15 is a longitudinal sectional detail view 10 taken on line 15—15 of Fig. 9.

Fig. 16 is a perspective view of the garment hanger shown in Fig. 9 in collapsed position.

In the use of garment hangers and particularly 15 in laundries and dry cleaning establishments, it becomes highly desirable to be able to quickly and easily collapse the hanger so that the same may occupy a minimum amount of space when not in use and to be able to easily and quickly extend or rearrange the parts of the hanger for 20 use. The present invention provides a construction whereby this advantageous result is easily and quickly accomplished.

In Fig. 1 I have shown a garment hanger which 25 consists of a cross bar 21, two converging supporting members 22 and 23 connected together and links 24 and 25 pivoted to the cross member 21 and to the supporting members 22 and 23. These various parts are constructed from paper 30 in a manner now to be described in detail.

The various parts of the garment hanger are 35 constructed from a blank 26 which consists of a strip of paper best shown in Fig. 3. This strip is scored transversely along lines 27, 28, 29, 30, 31 and 32 to form the cross bar 21, supporting 40 members 22 and 23 and links 24 and 25 together with two tabs 33 and 34 at the ends of the strip.

The blank is further scored longitudinally along lines 35 and 36 which extend throughout the tab 33, supporting member 22 and link 24 45 and similarly throughout the tab 34, supporting member 23 and link 25. The intermediate portion of the blank which forms the cross bar 21 is double scored as indicated at 37 and 38 which score lines lie in continuation of the score lines 35 and 36. By means of the various score lines 45 50 55 39 is provided with flanges 41 and 42 connected therewith. These parts are coextensive with the length of the strip.

The cross bar 21 of the garment hanger is reinforced by means of a strip of wood 43 best 50 shown in Fig. 4. This strip is of a width equal to the distance between the innermost of the score lines 37 and 38 and of a thickness equal to the distance between the respective score lines 55 60

37 and the respective score lines 38. The said strip is of a length substantially equal to the length of the cross bar 21.

In constructing the garment hanger the under-
5 side of the blank 26 is first coated throughout its entire extent with glue or other adhesive and the reinforcing member 43 placed upon the central portion of the band 39 between score lines 29 and 30. The flanges 41 and 42 are next turned
10 back upon the glued band 39 of the blank and upon the reinforcing member 43 and the same caused to adhere thereto. These flanges may be exactly one-half the width of the band 39 so that the edges thereof meet on the same may be
15 slightly larger so that an overlap is procured. In either event a flattened tubular construction is provided which is scored transversely along suitable lines forming the various parts of the hanger. It will be seen that the reinforcing
20 member 43 is imbedded within the portion of the tubular member forming the cross bar 21 and stiffens and reinforces the same. After the structure has been so glued together the various members are folded into the form shown in Fig. 1 by
25 bending the same at the various transverse score lines previously referred to. The tabs 33 and 34 are next secured together either by gluing, stapling, or otherwise to form a connecting portion 58 and a hole 44 punched through the same at the
30 center thereof.

In conjunction with the garment hanger a hook 45 is used. This hook comprises a shank 46 and a hook portion 47 at the uppermost end thereof. The lowermost end of the shank has
35 welded to it a cross head 48. The end 46 of the hook 45 is adapted to be inserted through the hole 44 in the connecting portion 58 and when the hook is in position as shown in Fig. 1, the cross head 48 lies along the under surface of said
40 tabs. The hook may be secured in position by means of two staples 51 and 52 which extend through the tabs 33 and 34 forming connecting portion 58 and which are clinched about the cross head 48. This construction permits of
45 swinging the hook about the cross head 48 as an axis.

In the design of the various parts of the garment hanger the proportions of the members are such that the combined length of the supporting
50 members 22 and 23 and the connecting portion 58 is substantially equal to the combined lengths of the two links 24, 25 and the cross bar 21. By so constructing the parts, the same may fold into collapsed position as shown in Fig. 8 in
55 which the supporting members 22 and 23 and the connecting portion 58 overlie the links 24 and 25 and the cross bar 21. The parts may thus be arranged in juxtaposition to occupy a minimum amount of space. The hook 45 is pivoted to the connecting portion 58 through the staples 51 and 52 and may be swung into substantially the plane of the hanger as shown in Fig. 8. When in such position the hanger is substantially planiform and the parts occupy a
65 minimum amount of space.

In using the device the hanger is grasped by the hook portion 47 and the same swung to its normal position. By drawing on said hook in a direction away from the cross bar 21 and holding said cross bar from movement, the supporting members are brought into converging relation which is accomplished by swinging the links 24 and 25 toward one another. The hanger is then ready for use. Due to the construction of
70 the hanger from paper the supporting members
75

22 and 23 are relatively flexible. In applying the hanger to a garment these parts of the hanger may readily bend to conform to the shape of the garment. This is particularly advantageous where a coat or other heavy garment is hung on the hanger. In Fig. 2 I have shown the hanger as applied to a coat 53. It will be noted how the supporting members bow to conform to the shape of the coat. As will become apparent the cross bar 21 may be used in the customary 10 manner for supporting trousers or other garments which may be conveniently folded intermediate their ends.

In Figs. 9 to 16 inclusive I have shown another form of the invention which is similar to that previously described, but which is constructed from two blanks of paper indicated at 61 and 62 in Figs. 10 and 11 and which are constructed and folded to form a flanged structure instead of a tubular structure as disclosed in the other 20 figures. The hanger shown in Fig. 9 consists of a cross bar 63, two converging supporting members 64 and 65 connected together at their converging ends and two links 66 and 67 connecting the other ends of said supporting members to 25 said cross bar.

The blank 61 is constructed from a strip of paper scored longitudinally at its ends along lines 68 and 69 to leave a central band 71 and flanges 72 and 73 issuing therefrom. The blank 30 is scored along transverse score lines 74, 75, 76, 77, 78, and 79 to provide portions 71a, 71b, 71c, 71d and 71e which form the various parts of the invention, and tabs 82 at the ends of the portions 71a and 71e. Between the score lines 78 35 and 79 the flanges 72 and 73 are cut away to leave the intermediate portion 71c of body portion 71 free from flanges. Likewise at the ends of the blank the flanges 72 and 73 are cut away to leave the tabs 82 free from flanges.

The blank indicated at 62 is scored longitudinally along two lines 83 and 84 to provide a central band 85 and flanges 86 and 87 projecting therefrom. This strip is scored transversely along lines 88, 89, 90, 91, 92 and 93 to provide 45 portions 85a, 85b, 85c, 85d and 85e which form parts which correspond with the members 63, 64, 65, 66 and 67 of the garment hanger and with tabs 81 at the ends of the portions 85c and 85e. The flanges 86 and 87 are cut away outwardly 50 from the score lines 90 and 91 to the ends of the strip so that the portions 85a, 85b, 85d, 85e and tabs 81 are free from flanges.

In conjunction with the garment hanger shown in Fig. 9, a reinforcing strip 96 is employed which 55 is identical with that shown in Fig. 4.

In the construction of the hanger the blanks 61 and 62 are coated with glue along the bands 71 and 85 of the same and the strip 96 attached to one or another of said blanks at the portions 60 71c or 85c thereof. The other blank is superimposed upon the said strip and the first named blank and the parts thus securely glued together. When the parts are properly arranged all of the members of the garment hanger are provided 65 with flanges. The portions 71c and 85c constitute the cross bar 63 and the flanges 86 and 87 on blank 62 form the flanges for this cross bar. The parts 71b and 85b and the parts 71d and 85d form the links 66 and 67 and the portions 71a, 70 85a and the portions 71e and 85e form the converging members 64 and 65. In securing the ends of the converging members 64 and 65 together, the tabs 82 are arranged in such position that the same overlap the portions 71a and 71e 75

of the hanger and likewise the tabs 97 of the blank 62 are arranged to overlie the portions 85a and 85e thereof. In this manner the ends of the converging supporting members 64 and 65 are securely held together. It will further be noted that the flanges 72 and 73 of blank 61 form the flanges for the supporting members 64 and 65 and likewise the links 66 and 67. At the juncture between the two supporting members 64 and 65 is provided an opening 98 which passes jointly through all of these parts. A hook 99 similar to the hook 46 is employed which is inserted through this opening. This hook differs from the other only in that the cross head 102 thereof is arranged at right angles to the plane of the hook portion 101. This cross head lies in the bight formed between the two supporting members 64 and 65 and does not have to be attached thereto with staples. When the parts are collapsed as shown in Fig. 1, the hook 99 is first removed from the hanger proper. When the garment hanger is erected or extended the flanges all project downwardly therefrom as shown in Figs. 13 and 14 and when the hanger is collapsed the flanges more or less straighten out and the entire device is more or less planiform.

The use of the invention disclosed in Fig. 9 is identical with that previously described and the description of the same will not be repeated.

The advantages of my invention are manifest. The device is simple and practical in construction. By means of the construction disclosed, sufficient supporting area is procured to properly support garments without causing unnecessary creases in the same. The garment hanger may be instantly collapsed or the parts thereof rearranged for use and when collapsed occupies a minimum amount of space. By constructing the garment hanger in the manner shown all of the hinges may be procured by scoring of the paper from which the hanger is constructed so that special hinges are eliminated. By the use of the reinforcing member in the cross bar a relatively inexpensive and light weight of paper may be used, thereby economizing in the cost of the device and making the converging members sufficiently flexible to conform to the shape of the garment.

Changes in the specific form of my invention, as herein disclosed, may be made within the scope of what is claimed without departing from the spirit of my invention.

Having described my invention, what I claim as new and desire to protect by Letters Patent is:

1. A garment hanger constructed from a strip of paper scored transversely intermediate its length to provide a cross bar, links connected to the cross bar and supporting members issuing from said links, means for securing said supporting members together and a support secured to said last named means.

2. A garment hanger constructed from a strip of paper, said strip being secured together at its ends and scored along closely spaced parallel lines disposed to either side of the attached ends and the center of the strip to form a cross bar, links issuing therefrom and supporting members issuing from said links and connected to one another, and supporting means secured to the hanger in proximity to the attached ends of the strip of paper.

3. A garment hanger constructed from a tube of flexible material bent transversely at predetermined localities intermediate its ends to form a cross bar, links connected therewith and supporting members issuing from said links, and means for connecting the ends of said supporting members together.

4. A garment hanger constructed from a tube of paper bent transversely at predetermined localities to form a cross bar, links connected therewith, supporting members issuing from said links, means for connecting the ends of said supporting members together, and a reinforcing member disposed within the portion of the tube forming said cross bar.

5. A garment hanger constructed from a strip of paper scored transversely intermediate its length to provide a cross bar, links connected to the cross bar and supporting members issuing from said links, said supporting members being adapted to be hingedly connected together at their ends, said links accommodating movement of said supporting members into juxtaposition with respect to said cross bar.

REYNOLDS GUYER.
